UNITED STATES PATENT OFFICE.

CHARLIE B. WADE, OF HAILEY, IDAHO.

GARMENT SUPPORTER.

Application filed February 3, 1923. Serial No. 616,749.

To all whom it may concern:

Be it known that I, CHARLIE B. WADE, a citizen of the United States, and a resident of Hailey, county of Blaine, and State of Idaho, have invented a new and useful Garment Supporter, of which the following is a specification.

My invention relates in general to a garment supporter and has reference more particularly to a device for supporting trousers to do away with the inconvenience of suspenders or belts.

The primary object of my invention is to provide means for conveniently supporting the trousers and also hold down the shirt to avoid the uncomfortable use of belts and suspenders. The invention possesses further objects and features which will appear as the description now proceeds with reference to the accompanying drawing, in which Figure 1 is a detail perspective view of the supporting device; Figure 2 a perspective view illustrating the application of the invention; Figure 3 is a detail view showing a portion 25 of the shirt equipped with a button for use in combination with the device; Figure 4 is a detail view in side elevation illustrating the application of the invention showing the cooperative relation of the shirt with the same; Figure 5 is a vertical section on the line 5—5 of Figure 4; and Figure 6 a perspective view of modified form of garment supporter.

Referring now to the drawing in detail A 35 represents a pair of ordinary trousers having the usual band B. According to my invention I propose to equip the inside of the band B with buttons as at (5) and to provide a complementary button (6) at opposite sides of the shirt C. In some instances to allow for adjustment of the same the side of the shirt may be equipped with button-holes such as (7) so that the height of the button (6) may be adjusted.

45 The supporter per se comprises an irregular shaped plate (8) which is stamped or otherwise formed from a sheet metal blank to leave a slightly curved elongated slot (9) in the top thereof, the slot being enlarged

as at (10), so that in applying the device to 50 the inside of the band of the trousers the buttons (5) may first be introduced to the slot through the enlarged opening at (10), then by manipulating the device, as well as the band, the buttons may be retained in the 55 semi-circular ends (11) of the slot. The shoulders provided as at (12) will maintain the buttons in place.

Depending downwardly from the slot (9) is a bifurcated extension (13), the same terminating in round ends (14) with the slot (15) between the same, the slot terminating in a substantially circular opening (16) as shown.

In using the device the trouser band is 65 first equipped with a pair of the supporting members as shown in Figure 2 so that when the shirt is worn the buttons (6) carried thereby may be slipped into the slots (15) where they will be seated in the openings 70 (16) as best shown in Figure 4, and the shirt in this way may be relied upon to support the trousers, thus avoiding the necessity of wearing suspenders or belts.

The modified form of garment supporter 75 (17) shown in Figure 6 presents substantially the same features as the one previously described, but is made of different material. It comprises in its principal features a wire (18) bent to define the elongated 80 slot (19) with rounded ends (20) and the downwardly opening slot (21) adapted to receive the button secured to the shirt. A spacing member (22) is employed to lend 85 rigidity to the device.

I claim:

As a new article of manufacture, a garment supporter formed of a single piece of metal of substantially T form having a long horizontal branch at its upper end and a depending central branch, the long branch having holes therein at its respective ends adapted to engage with buttons at the waist line of a pair of trousers, and the central short branch having its lower end formed 90 with a substantially inverted U shaped hole to receive the button of a shirt.

CHARLIE B. WADE.
